CLAIM

I claim the ornamental design for an extendable lamp for a cabinet, as shown and described.

DESCRIPTION

FIG. 1 is a perspective view of an extendable lamp for a cabinet showing my design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof; and,

FIG. 8 is a perspective schematic view illustrating an application of the extendable lamp for a cabinet showing my design.

1 Claim, 5 Drawing Sheets
